his Attorneys.

UNITED STATES PATENT OFFICE

JOHN H. REEDY, OF HAMILTON, OHIO, ASSIGNOR TO THE CHAMPION COATED PAPER COMPANY, OF HAMILTON, OHIO, A CORPORATION OF OHIO

PAPER-WINDING APPARATUS

Application filed March 15, 1929. Serial No. 347,368.

The present invention relates to apparatus for reeling or winding up a web of paper and more particularly to an improved smoothing roll.

Difficulties in reeling paper are frequently encountered when for one reason or another the web of paper is wrinkled or cockled. Under these conditions and also at other times the paper may wind very unevenly, with the production of permanently creased portions in spite of the continuous attention of an operator. This trouble is particularly pronounced with light weight coated papers.

The object of the invention is to provide a reel which reduces or eliminates these difficulties in winding paper.

The invention will be described with reference to the accompanying drawings, of which

Fig. 1 is a diagrammatic representation of a reeling assembly in use in the paper-making industry;

Fig. 2 is a front elevation of the improved smoothing roll of the invention;

Fig. 3 is a side elevation of the same; and Fig. 4 is a vertical cross-section of a portion of the rim of the improved smoothing roll, showing the distinctive features of the invention.

The invention may employ the same assembly as that shown in Fig. 1. 1 is a web of paper which may come, for example, from the drying festoons of a coating machine. It passes around the guide roll 2 to the smoothing roll 3 and then is wound into the roll of paper 4 on the core 5. Smoothing roll 3 is driven from the pulley 6 by means of the belt 7, pulley 6 being connected to a motor or other source of power not shown. The core 5 is keyed to the shaft 8. 9 is a weight which presses down on the shaft 8.

It is well known to provide the surface of the smoothing roll 3 with a number of parallel grooves. One series of grooves extends from the right edge of the roll and another from the left, the two series meeting in the middle of the convex surface of the roll, forming a number of broad V's. By rotating the roll in the direction of the apex of the V, the paper is spread out from the center toward the edges. Although this device

helps in the production of a well wound roll, it is not always successful in this.

The present invention relates to certain improvements in the above described smoothing roll, more particularly shown in Figs. 2, 3 and 4.

A number of grooves 12 are cut in the convex surface of the roll, the arrangement of the grooves being substantially the same as described above. The cross-sectional view, Fig. 4, shows the preferred shape of these grooves. The forward face of the groove 13 slopes away from the roll surface at a low angle. The rear face 14 of the groove forms almost a right angle with the roll surface. This preferred shape may be designated as sulcate or furrow shaped. The forward and rear edges of the grooves are smoothed off to prevent tearing of the paper.

Each groove is perforated with a large number of small holes 15 extending along each groove. These holes permit the direct passage of air from the roll surface to the interior. In practice, a roll 20 inches in diameter with grooves spaced two inches apart, and with circular holes $\frac{1}{8}$ inch in diameter and spaced in the grooves one inch from each other, has proved satisfactory.

The reel may be used for coated or uncoated paper.

The operation of this device has proved very successful. The paper is wound up without trouble into a firm, uniform roll, substantially free from creases and other imperfections.

It will be seen that the invention comprises a smoothing roll for reeling webs of paper, the peripheral surface of which is provided with a plurality of V-shaped longitudinal grooves, preferably sulcate in section, arranged in parallel spaced relation, the bed of the grooves being pierced by a plurality of perforations.

I claim:

1. A smoothing roll for reeling webs of paper, the peripheral surface of which is provided with a plurality of V-shaped longitudinal grooves arranged in parallel spaced relation, the apexes of said grooves extending in the direction of motion of the

surface of the roll, and the beds of the grooves being pierced by a plurality of perforations, permitting the direct passage of air from the surface of the roll to the interior.

- 5 2. A smoothing roll for reeling webs of paper, the peripheral surface of which is provided with a plurality of V-shaped longitudinal grooves, of sulcate cross-section, arranged in parallel spaced relation, the apexes of said grooves extending in the direction of motion of the surface of the roll, and the beds of the grooves being pierced by a plurality of perforations, permitting the 15 direct passage of air from the surface of the roll to the interior.

In testimony whereof, I affix my signature.
JOHN H. REEDY.
